UNITED STATES PATENT OFFICE.

JOSEPH P. HULDER, OF NEW YORK, N. Y., ASSIGNOR TO LUDWIG AND COMPANY, A CORPORATION OF NEW YORK.

TRACKING DEVICE.

1,090,310.

Specification of Letters Patent. Patented Mar. 17, 1914.

Application filed March 29, 1912. Serial No. 687,057.

To all whom it may concern:

Be it known that I, JOSEPH P. HULDER, a citizen of the United States, and a resident of the city of New York, county and State of New York, have invented certain new and useful Improvements in Tracking Devices, of which the following is a full, clear, and exact specification.

My invention relates to a device for automatically maintaining accurate operative relation between the note perforations in a traveling music sheet and the corresponding apertures in a tracker bar.

The principal object of this invention is to provide an automatic device which is self adjustable to and operable with note sheets of various width, be the same wider or narrower than standard.

In operating an instrument provided with my improved tracking device, it is merely necessary to insert the music roll in the customary manner, when, by reason of the construction and arrangement of parts of the device, it will adapt itself to the width of the sheet and maintain the perforations thereof in accurate registration with the tracker bar openings during the playing of the sheet, without further attention by the operator.

In carrying out the invention I employ a guide opening disposed relatively to one edge of the sheet, and an edge guide for contact with the opposite edge co-acting to govern the movement of a regulator pneumatic, whereby, upon any deflection of the sheet, normal relation will be restored.

A further advantage of my invention consists in providing means for holding the edge guide out of contact with the edge of the sheet during the re-rolling of the sheet, so as to prevent damaging the edge thereof.

In the accompanying drawings illustrating my invention Figure 1 is a rear elevation of my improved device. Fig. 2 is a plan view partly in section through the longitudinal center line of the tracker bar.

Fig. 3 is a front elevation of the tracker showing the sheet guides and correlated parts. Fig. 4 is a section through the valve block. Fig. 5 is a front end view of the same. Fig. 6 is a view of the inner face of the valve cap, and Fig. 7 is a view of the valve cap looking edgewise.

(1) designates a perforated note sheet which is arranged to be drawn over the

note apertures in a tracker bar (2) from a carrying roll (3) on to a take up roll (4). These rolls are supported on longitudinally movable spindles (5) which are mounted in the tracker box in the customary manner and are provided, at one end, with the usual thrust bearings (6) tending to force the rolls from right to left, as shown in Fig. 1.

(7) indicates a regulator pneumatic in which a partial vacuum is normally maintained by communication with the suitable exhaust chest (8). A rod (9) connects the movable leaf of said pneumatic with a pivoted bar (10) having arms which abut against the left hand ends of the spindles (5) so that upon decreasing the tension in the pneumatic (7) the consequent collapse of its movable leaf will cause the rolls to be shifted in a direction opposite to and against the thrust of the bearings (6). It is apparent, therefore, that the position of the note sheet is controlled by varying the tension in the regulator pneumatic.

The guide opening or air intake (11) is disposed in the path of travel of one edge of the note sheet and is arranged to be partially closed thereby when said sheet is traveling accurately. This opening communicates through a flexible tube (12) with a bypass (13) formed in the valve block (14), and connecting with an exhaust port (15), also formed in said block, the rear end of which port communicates through a flexible tube (34) with the regulator pneumatic.

(16) represents a laterally movable edge guide which is pivotally mounted as at (17) to the rearwardly extending arm (18) carried on the tracker bar for contact with the edge of the sheet opposite to the guide opening (11). A rod (19) connects the edge guide with the valve cap (20), pivotally secured as at (21) to the valve block (14). The spring (22) acting against the valve (20) tends to press it inwardly so as to cause it to follow the movement of the edge guide.

The valve block is provided with an exhaust channel (23) in addition to the above mentioned exhaust port (15) and bypass (13). The rear end of this channel communicates through a flexible connection (33) with the exhaust chest (8). The forward ends of the channel (23) and port (15) open in the front face of the valve block, constituting the seat for the valve cap (20).

- The valve cap (20) is formed with a groove (24) serving as an exhaust passage for establishing variable communication between the exhaust channel (23) and the port (15).
 5 The upper arm (25) of this groove is made large enough to be in constant and unrestricted communication with the exhaust channel, while the lower arm (26) is made of a height equal to the height of the opening (11) and disposed so that when the valve cap is swung outwardly it will gradually close the port (15) and vice versa, thereby controlling the area of said port so as to govern the exhaust of the regulator pneumatic upon any deflection of the sheet. As the height of the air intake (11) is equal to the height of the arm (26) of the valve, the areas of the intake and exhaust openings will be a function of their length, or in other words, the quantity of air which is admitted to the regulator pneumatic through the opening (11) will depend upon and vary with the relative position of the edge of the sheet with regards to said opening, while the quantity of air that is exhausted from the pneumatic will depend upon and vary with the area of the opening of the port (15) which area is governed by the movement of the valve cap following the lateral movement of the other edge of the sheet.
 10 The intake (11) and the edge guide (16) are spaced equally distant from but on opposite sides of the center of the tracker bar, and in setting up the device, the valve (20) is adjusted so that when the note sheet is in normal position, the area of the exhaust port (15) will be equal to the area of the intake. By referring to Fig. 3, it will be seen that as the sheet shifts from right to left, the intake (11) is gradually opened, while at the same time the exhaust port (15) is being gradually closed in a corresponding amount, and vice versa.
 15 The valve block is preferably hinged as at (27) to the side of the tracker box, and provided with a set screw (28) whereby it may be readily adjusted to bring the exhaust port (15) into correct initial position with respect to the arm (26) of the groove in the valve cap. After the valve has been properly adjusted, the device will operate with note sheets of various width without further adjustment.
 20 In order to withdraw the edge guide from contact with the edge of the sheet during the re-rolling operation, I provide a pneumatic (29) which communicates with the exhaust chest (8) and is connected by a string (30) with the rock arm (31) of the edge guide. While the instrument is being played this pneumatic is collapsed, and consequently the string is slack, permitting free play of the edge guide to follow the movement of the sheet, but while the sheet is be-
 25

ing re-rolled, in the customary manner, the pneumatic is expanded by its spring (32) so as to draw the string taut and hold the edge guide away from the edge of the sheet.

The operation of the device is dependent upon having an equal ratio between the areas of the intake (11) and the exhaust port (15) when the note sheet is in normal position, and maintaining this ratio constant during the travel of the sheet. The width of a note sheet is distributed equally on both sides of its central line. The difference in the width of the various commercial note sheets is, however, comparatively slight. It will be seen, therefore, that a sheet which is wider or narrower than standard merely decreases or increases the extent of said areas without disturbing the ratio between them, and that consequently, the device is self adjustable to sheets of various width.

The mode of operation of my invention is as follows: When the sheet is in normal relation to the note openings in the tracker, the area of the intake opening (11) will be equal to the area of the exhaust port (15), and all the air entering said opening will be sucked through the by-pass (13) into the exhaust chest. As, however, the sheet is deflected from its true path of travel, one edge thereof will tend to cover or uncover the opening (11), depending upon the direction of the deflection, and the edge guide (16) with its connected valve (20) following the movement of the other edge of the sheet, will tend to open or close the exhaust port (15) in a corresponding amount. When, by reason of the deflection of the sheet, the area of the exhaust port becomes greater than the area of the intake, the effective suction, tending to cause the regulator pneumatic to collapse, will be proportionate to the difference of said areas, and similarly, when the area of the intake becomes greater than the area of the exhaust port, a quantity of air in proportion to the difference of said areas will enter into and tend to expand the regulator pneumatic. The consequent movement of the movable leaf of the regulator pneumatic will tend to cause the sheet to be shifted in a direction opposite to the direction of its deflection and thereby restore normal relation.

In the foregoing specification, I have described the best mode in which I have applied the principle of my invention, but it will be understood by those skilled in the art, that the principle thereof may be applied in other modes, as, for example, to shift the position of a movable tracker with respect of a fixed music roll.

What I claim as my invention is:

1. In combination, a pneumatic having an exhaust port, a guide opening disposed under one edge of a note sheet and communicating with the pneumatic; an edge guide

contacting with the opposite edge of the sheet; a valve operatively connected with the edge guide and controlling the exhaust port of the pneumatic; and means operated by the pneumatic for maintaining proper tracking relation between the note sheet and the tracker.

2. In combination, a note sheet; a guide opening located under one edge of the note sheet and partially covered thereby when the sheet is properly tracking; a laterally movable edge guide contacting with the opposite edge of the sheet; a pneumatic communicating with the guide opening and provided with an exhaust port; a valve operatively connected with the edge guide for controlling the effective cross sectional area of the exhaust port and equalizing it with the uncovered area of the guide opening; and means operated by the pneumatic for maintaining proper relation between note sheet and the tracker.

3. In combination with a traveling note sheet, and a tracker bar; a guide opening disposed in the path of and partially covered by one edge of the sheet when traveling accurately; a laterally movable edge guide contacting with the other edge of the sheet; and means for restoring normal relation between the tracker and the sheet upon any deflection of the latter, said means being governed by means which include the guide opening and the edge guide.

4. A tracking device for an instrument employing a traveling note sheet, comprising a guide opening, located under one edge of the note sheet and partially covered

thereby when the sheet is properly tracking; a laterally movable edge guide contacting with the opposite edge of the sheet; a pneumatic communicating with the guide opening and provided with an exhaust port; exhaust apparatus communicating with the exhaust port of said pneumatic; a valve operatively connected with the edge guide for controlling the exhaust port adapted to be moved by the shifting of the sheet to gradually open or close said port, said valve being adjusted so that when the sheet is in normal position the effective cross sectional area of the exhaust port will be equal to the uncovered area of the guide opening, and that when the sheet shifts, the area of the exhaust port will be increased or decreased in inverse ratio to the decrease or increase of the uncovered area of the guide opening, thereby varying the air tension in the pneumatic; and means operative upon a variation of the air tension in the pneumatic to restore the sheet to normal position.

5. In a tracking device the combination of an edge guide, an expanding spring for drawing and holding the edge guide away from the sheet, and a pneumatic for compressing the spring during the tracking operation to permit the edge guide to contact with the edge of the sheet.

In witness whereof I have hereunto signed my name in the presence of two subscribing witnesses.
